Robert R. Cox Inventor

L. N. Willis
Attorney.

UNITED STATES PATENT OFFICE.

ROBERT R. COX, OF OSCEOLA, NEBRASKA.

BUCKET HOLDER.

Application filed April 18, 1922. Serial No. 554,650.

To all whom it may concern:

Be it known that I, ROBERT R. Cox, a citizen of the United States, and a resident of Osceola, in the county of Polk and State of Nebraska, have invented certain new and useful Improvements in Bucket Holders, of which the following is a specification, reference being had to the accompanying drawings.

10 This invention has relation to certain new and novel improvements in bucket holders and comprises an attachment adapted to be adjustably secured to a ladder to hold a paint bucket to the outer side of the rail of 15 the ladder so that the bucket is at all times within convenient reach of the painter upon the ladder; and the primary object of my invention is to provide a bucket holder of a simple and inexpensive nature and of a compact and durable construction, arranged so 20 that the bucket holder can be adjustably attached to a ladder with ease, accuracy, and dispatch.

With these and other objects in view, the 25 present invention consists in the combination and arrangement of parts as will be hereinafter more fully described and finally pointed out in the appended claims, it being further understood that changes in the specific structure shown and described may be 30 made within the scope of the claims without departing from the spirit of the invention.

In the accompanying drawings, forming 35 a part of this specification, and in which like numerals of reference indicate similar parts in the several views:—

Figure 1 shows a broken side view of a 40 ladder, showing my bucket holder as attached thereto.

Figure 2 is a face view of a broken portion of a ladder showing how the paint bucket is held to the outer face of a ladder rail.

45 Figure 3 shows the manner of securing my bucket holder to a step ladder.

In my present invention I provide a ladder attachment comprising a bucket holder adapted to be removably secured to a ladder.

50 As shown, my invention includes a sheet metal member which is bent U-shaped and comprises a central portion 1, and two opposite side portions 2, 2 which are held in parallel spaced relation. These portions 2, 2 55 are of such a width that they will conven-

iently stride the rail of a conventionally constructed ladder. As shown, the holder has opposite end portions 3, bent back to form ears which are apertured as are the side portions 2, 2 adjacent, so that suitable rivets 4 are held within these apertures. Pivotedly held upon these rivets 4 and between the ears are the rung hooks H. These hooks H are adapted to hook over the rung B of a ladder. Each side member 2 is provided with a V-shaped portion 5 stamped out of the metal body to provide an integral supporting member, these members being held in parallel spaced relation relative to the sides 2, 2 and are adapted to support and receive the bail E of a suitable paint or other bucket D. As shown, each U-shaped member is provided with two side supporting members 5 as well as two rung hooks H so that the bucket holder may be 75 placed astride of either the right or the left rail of the ladder.

My invention is particularly adapted to be used as a paint bucket holder and offers convenient means for supporting a 80 paint bucket in a handy position so that the painter upon the ladder can at all times conveniently reach the contents of the bucket.

As shown, the supporting member 5 upon the outside is the one adapted to receive the 85 bucket, although, it should be understood, as shown, a second bucket could be placed upon the opposite supporting member 5 upon the inside so that one holder can be made to do the service of supporting two buckets.

While my invention is especially adapted to be used by painters, the same can also be used by window washers, and wherever a bucket is used by workmen upon a ladder.

In Figure 3, I have shown a modification 95 wherein the holder is attached to the rail A' of an ordinary step ladder. As disclosed, I provide an auxiliary hook C. Where these holders are especially adapted to be used in connection with step ladders, the hook H is 100 made of such a size that the same can be hooked over the tread B' of a step ladder. In window washing, and cleaning wood work, where a step ladder is used, the holder provides a convenient and efficient means for 105 holding the water bucket.

It is, of course, understood that these bucket holders are made in different sizes so as to be capable of being used in connection with different sized ladders and if desired, 110

the side members 2, 2 may be made of such a length that they extend downward a distance sufficient so that the upper edge of the paint bucket will rest against one of the 5 side portions 2, 2.

While I have shown the holder as made out of sheet metal, it should be understood that they may be cast.

An incident of convenience in this device 10 for supporting a paint bucket is that the bucket can be easily shifted from side to side and can be raised and lowered as the workman progresses with his work.

The holder is further simple and inexpensive in construction and both durable and 15 efficient in operation.

Having thus described my said invention, what I claim as new and desire to secure by 20 U. S. Letters Patent is:—

1. A bucket holder adapted to be removably secured to a ladder, comprising a sheet

metal member bent U-shaped with opposite end portions bent back to form ears which are apertured, rivets within said apertures, V-shaped portions being stamped out of said metal body to provide supporting members adapted to receive the bail of a bucket, and a hook secured to each rivet whereby when 25 said member is placed astride of the rail of a ladder one of said hooks may be brought into engagement with a rung of the ladder, as, and for the purpose set forth.

2. A holder of the character described, comprising a U-shaped member adapted to be placed astride of the rail of a ladder, having an outwardly directed bucket-bail receiving ear, and in combination with a hook 30 pivotally secured to said holder, the hook being adapted to be brought into engagement with the rung of a ladder.

In testimony whereof I affix my signature.

ROBERT R. COX.
